UNITED STATES PATENT OFFICE.

AUGUSTA J. ZAMZOW, OF BARABOO, WISCONSIN.

DRAINING DEVICE.

1,163,877.

Specification of Letters Patent. Patented Dec. 14, 1915.

Application filed July 30, 1915. Serial No. 42,812.

To all whom it may concern:

Be it known that I, AUGUSTA J. ZAMZOW, a citizen of the United States, residing at Baraboo, in the county of Sauk, State of Wisconsin, have invented certain new and useful Improvements in Draining Devices; and I do hereby declare the following to be a full, clear, and exact description of the invention, such as will enable others skilled 10 in the art to which it appertains to make and use the same.

This invention relates to improvements in draining devices and particularly to devices for draining clothes when they are lifted 15 from the wash boiler.

One object of the invention is to provide a novel and efficient device which can be placed on one end of the wash boiler in a convenient position to receive the clothes as 20 they are lifted from the boiler.

Another object is to provide a device of this character which is provided with a draining means to permit the water from the clothes to run back into the boiler.

25 A further object is to provide a novel means for closing the outlet so that the device can be lifted from the boiler and carried without danger of the water dripping to the floor.

30 Other objects and advantages will be apparent from the following description when taken in connection with the accompanying drawing.

In the drawing: Figure 1 is a side elevation of my invention applied to a wash boiler, Fig. 2 is a top plan view, Fig. 3 is a section on the line 3—3 of Fig. 2, and Fig. 4 is a bottom plan view of the drainer.

Referring particularly to the accompanying drawing, 10 represents the wash boiler which is preferably elongated, and on one end of which my drainer is adapted to be placed. The drainer comprises a receptacle having a bottom 11 with the 15 straight and vertical wall 12 and the curved inclined wall 13 disposed at the side opposite to the wall 12 and connected to the said wall 12 by the vertical wall 14. In the bottom 11, adjacent the wall 12 is a perforated area 15, and secured to the lower

side of the bottom surrounding the perforated area is a downwardly tapering discharge spout 16. Hinged to one edge of this spout is a valve 17 provided with a suitable leather packing 18 adapted to bear 55 against the lower edge of the spout and thus prevent the escape of water while the drainer is being carried. Secured to the bottom, at a point centrally of the lower edge of the curved wall are a pair of spaced 60 lugs 19 which are adapted to straddle the upper edge of the end of the wash boiler to hold the drainer from slipping therefrom. The valve 17 is provided with a projecting lip 20 to which is connected one end of a 65 coil spring 21. Carried by the other end of the spring are a pair of hooks 22 and 23, the former of which serves as a finger hold, while the latter is adapted to engage over the upper edge of the wall 12, to hold the 70 valve 17 firmly against the lower edge of the spout 16.

In the operation of the device the drainer is placed over one end of the wash boiler with the lugs 19 embracing the upper edge 75 of the wall thereof. The hook 23 is released from the upper edge of the wall 12 so as to permit the valve 17 to swing into open position. The clothes from the boiler can then be lifted up and placed in the 80 drainer, the water therefrom passing through the openings at 15 and through the spout back into the boiler. When it is desired to carry the drainer with the clothes to another place, the hook 23 is engaged 85 over the edge of the wall 12 so as to close the valve 17. Then by grasping the handles 24, the drainer can be lifted from the boiler and conveniently carried without danger of the water dripping therefrom. 90

What is claimed is:

A clothes draining device comprising a receptacle adapted to be placed over one end of a clothes boiler, means carried by the drainer for engagement with the upper edge 95 of the wall of the boiler to prevent slipping of the drainer, a perforated area formed in the bottom of the drainer, a downwardly tapering spout secured to the bottom of the drainer and surrounding the perforated 100

area, a valve movably connected to the lower end of the spout, a resilient element connected to the free edge of the valve, and means carried by the other end of the resilient element for engagement with one edge of the drainer to hold the valve in closed position.

In testimony whereof, I affix my signature, in the presence of two witnesses.

AUGUSTA J. ZAMZOW.
